INVENTOR
Jacob C. Jorgensen
By his Attorney,
Harlow H. Davis

UNITED STATES PATENT OFFICE

JACOB C. JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY

MACHINE FOR SHAPING SHOE UPPERS

Original application filed April 16, 1929, Serial No. 355,566. Divided and this application filed July 8, 1931. Serial No. 549,400.

This invention relates to means for supporting shoes in machines for operating thereon, and in one aspect has especially in view the provision of improved shoe-supporting means in machines for lasting the heel ends of shoes, this application being a division of a copending application Serial No. 355,566, filed on April 16, 1929, upon which Letters Patent No. 1,852,015 were granted on April 5, 1932. It is to be understood, however, that the invention is not limited in its applicability to machines of that particular character.

In machines for lasting the heel ends of shoes by means of wipers it is desirable that the wipers apply substantially equal pressures on the opposite sides of the heel seat. An object of the present invention is to provide in such a machine improved shoe-supporting means so constructed as readily to obtain that result in the operation of the wipers. For the purpose in view the construction herein shown comprises a shoe-supporting member provided with the usual last pin or spindle and mounted for movement about an axis extending lengthwise of the shoe substantially in the location of the heel seat, so that the shoe may be tipped laterally without any substantial lateral displacement of portions of the sides thereof that are near the heel seat and are engaged by the usual heel-clamping band. This permits each shoe to be tipped as required to present its heel seat in substantially parallel relation to the plane of the wipers, notwithstanding such variations as there may be in the locations of the spindle holes in different lasts, without substantially altering the position of the shoe laterally in relation to the wipers and without undesirably affecting the relation of the shoe to the heel band. As illustrated, the above-mentioned supporting member is so mounted and controlled as to permit it to be moved as described by the action of the last thereon as the latter is tipped by the operator in presenting the work to the machine or is further tipped by the pressure of the wipers on the heel seat. The construction shown further comprises novel means whereby the supporting member is normally main-

tained yieldingly in a substantially central position from which it may be moved in one direction or the other for the purpose in view.

The novel features of the invention will now be more particularly described by reference to the accompanying drawing and pointed out in the claims.

In the drawing,

Fig. 1 is a view, partly in front elevation and partly in section, illustrating the novel shoe-supporting means in its relation to operating instrumentalities of the heel-seat lasting machine disclosed in the above-mentioned Letters Patent, and

Fig. 2 is a section on the line II-II of Fig. 1.

As more fully illustrated and described in the above-mentioned Letters Patent, the machine comprises wipers 10 for wiping the marginal portion of the heel end of the upper inwardly over a sole or insole on a last at the opposite sides of the heel seat simultaneously, a heel band 12 which embraces and clamps the upper about the heel end of the last by engaging its end and side faces in locations near the heel seat, and a jack post 14 mounted for swinging movement in a direction lengthwise of the shoe from a work-receiving position into position to present the last and shoe within the heel band 12, the jack post carrying a spindle 16 arranged to project into the spindle hole in the heel end of the last. After such movement of the jack post the heel band is operated automatically to clamp the shoe and the wipers 10 are then operated to wipe the margin of the upper inwardly over the sole or insole and to press it firmly down prior to the driving of upper-fastening tacks.

It is desirable that in the heel-seat lasting operation the wipers 10 shall wipe the margin of the upper inwardly and press it down with substantially equal pressures at the opposite sides of the heel seat. In different lasts, however, the spindle holes are not always arranged in the same angular relation to the bottom faces of the heel ends of the lasts. In order that the heel seat of each shoe may be positioned in substantially parallel

relation to the plane of the wipers, notwithstanding such variations in the construction of different lasts, the upper end of the jack post 14, in the construction herein shown, is 5 provided with a slot arranged to extend laterally of the shoe, and the portions of the post at the opposite sides of the slot have upper faces 18 curved about an axis extending lengthwise of the shoe substantially in the 10 location indicated at the point *x* to provide a guideway. Mounted in this slot is the lower portion of a shoe-supporting member or block 20 which carries the spindle 16, this block having shoulders curved similarly to 15 the faces 18 and seated thereon. The block 20 and the spindle 16 are thus movable laterally of the shoe about an axis extending lengthwise of the shoe and located, as herein illustrated, substantially at the heel-seat face 20 of the shoe midway between its opposite sides, so that the shoe may be tipped to position the opposite sides of the heel seat in the same relation to the plane of the wipers without any substantial lateral bodily displacement 25 of portions of the sides of the shoe that are located near the heel seat.

The block 20 and the spindle 16 are normally centralized by means including a coil spring 22 which is mounted in a recess in the 30 lower end of the block with its axis extending widthwise of the shoe and is held under compression between two disks 24 slidingly movable in the recess in which the spring is mounted. The right-hand disk 24 is normally seated against a shoulder on the block, and the other disk against a lug 26 which is detachably fastened to the block. The block 20 is provided with a transverse slot extending across it laterally of the shoe below the 35 spring 22, and projecting upwardly through this slot and into the recess in the block are lugs 28 which are fastened to the post 14 and are normally in engagement respectively with the outer faces of the two disks 24. It 40 will thus be evident that while the block 20 is normally centralized by the spring 22, the disks 24 and the lugs 28, it may be moved in either direction along the curved guideway 18 against the resistance of the spring which is then compressed by the action of one or the other of the lugs 28, as illustrated in Fig. 1. The operator may effect such movement of the block and the spindle 16 by tipping the last in one direction or the other 45 as he presents the shoe to the machine, in order to position the heel seat in what appears to him to be the proper plane for the action of the wipers. If the shoe, however, as thus presented is not exactly in position for the 50 wipers to apply equal pressures at the opposite sides of the heel seat, it may be further tipped in the lasting operation by the pressure of one or the other of the wipers thereon. In order to limit the extent of movement of the block 20 there is further pro-

vided a screw 30 which is mounted in the post 14 and projects into a slot 32 in the block.

While the axis *x* is herein illustrated as located on the heel-seat face of the insole *a*, it will be understood that the position of the axis in relation to the shoe bottom may vary somewhat, as in the operation of the machine, on shoes of different sizes. Such variation, however, is not enough to result in any substantial lateral displacement of the portions of the sides of a shoe near the heel seat by the small amount of tipping movement necessary to secure equalization of pressure on the heel seat, and references in the claims to the axis as located substantially at the heel seat are intended to comprehend such small variations as may result, for example, from differences in size.

In the appended claims the term "sole" is used as a generic term to define that part over which the margin of the upper is wiped in the lasting operation, regardless of the type of shoe operated upon, and the term "heel seat" also is used to designate generally that face of the heel end of the sole over which the upper is wiped.

Having described the invention, what I claim as new and desire to secure by Letters Patent of the United States is:

1. In a machine having wipers for wiping the margin of an upper into lasted position about the heel end of a shoe on a last at the opposite sides of the heel seat simultaneously, a shoe support comprising a member mounted for movement about an axis extending lengthwise of the shoe substantially in the location of the heel seat to permit the shoe to be tipped laterally to provide for substantial equalization of the pressures of the wipers on the shoe bottom at the opposite sides of the heel seat without any substantial lateral displacement of portions of the shoe near the heel seat, said member being so controlled as to permit it to be moved about its axis in response to pressure of the wipers on the shoe.

2. In a machine having wipers for wiping the margin of an upper into lasted position about the heel end of a shoe on a last at the opposite sides of the heel seat simultaneously, a shoe support comprising a member mounted for movement about an axis extending lengthwise of the shoe substantially in the location of the heel seat and substantially midway between the opposite sides of the shoe to permit the shoe to be tipped relatively to the wipers to position the heel seat in proper relation to the plane of the wipers without any substantial lateral displacement of portions of the sides of the shoe near the heel seat, said member being movable about its axis in response to tipping movement of the shoe and last effected by the operator in presenting the work to the machine.

3. In a machine having wipers for wiping the margin of an upper into lasted position about the heel end of a shoe on a last at the opposite sides of the heel seat simultaneously, 5 a work support comprising a spindle for engaging the heel end of the last in its spindle hole, said spindle being mounted for movement about an axis extending lengthwise of the shoe substantially in the location of the 10 heel seat by action of the last thereon to permit the shoe and last to be tipped relatively to the wipers to position the heel seat in proper relation to the plane of the wipers without any substantial lateral displacement 15 of portions of the shoe near the heel seat.
4. In a machine having wipers for wiping the margin of an upper into lasted position about the heel end of a shoe on a last at the opposite sides of the heel seat simultaneously, 20 a work support comprising a spindle for engaging the heel end of the last in its spindle hole, said spindle being mounted for movement about an axis extending lengthwise of the shoe substantially in the location of the 25 heel seat to permit the shoe and last to be tipped relatively to the wipers to position the heel seat in proper relation to the plane of the wipers without any substantial lateral displacement of portions of the shoe near the 30 heel seat, and spring means for normally centralizing said spindle with respect to movement about its axis while permitting such movement of the spindle by the tipping of the last.
5. In a machine having wipers for wiping the margin of an upper into lasted position about the heel end of a shoe on a last at the opposite sides of the heel seat simultaneously, a work support comprising a spindle 40 for engaging the heel end of the last in its spindle hole, a member on which said spindle is supported, and means provided with an arc-shaped guideway along which said member is movable about an axis extending lengthwise of the shoe substantially in the location of the heel seat by action of the last on the spindle to permit the shoe and last to be tipped relatively to the wipers for substantially equalizing the pressures of the 45 wipers on the opposite sides of the heel seat without any substantial lateral displacement of portions of the sides of the shoe near the heel seat.
6. In a machine having wipers for wiping the margin of an upper into lasted position about the heel end of a shoe on a last at the opposite sides of the shoe bottom simultaneously, a work support comprising a spindle for engaging the heel end of the last 55 in its spindle hole, a member on which said spindle is supported, and means provided with an arc-shaped guideway along which said member is movable about an axis extending lengthwise of the shoe in such relation to the bottom of the shoe as to permit 60 lateral tipping movement of the shoe and last relatively to the wipers without any substantial lateral displacement of portions of the sides of the shoe near the wipers, said member being thus movable in response to 70 tipping movement of the shoe and last effected by the operator in presenting the work to the machine.
7. In a shoe machine having means for operating on shoe materials on a last, a work support comprising a spindle for engaging the last in its spindle hole, said spindle being mounted for tipping movement about an axis extending lengthwise of the last substantially in the location of a shoe bottom, 75 and spring means for normally centralizing said spindle with respect to such tipping movement while permitting it to be tipped by the action of the last hereon.
8. In a shoe machine having means for operating on shoe materials on a last, a work support comprising a member having a guideway curved about an axis extending lengthwise of the last, a block curved to fit 80 said guideway and provided with a spindle for engaging the last in its spindle hole, and a coil spring arranged with its axis extending widthwise of the last to cooperate with said member and block to determine a normal 85 centralizing position of the block while permitting it to be moved in opposite directions along the guideway.
9. In a shoe machine having means for operating on shoe materials on a last, a work support comprising a jack post having at its 90 upper end a slot extending laterally of the last and having a guideway curved about an axis extending lengthwise of the last, a block mounted in said slot and curved to fit said guideway, said block being provided with a spindle for engaging the last in its spindle hole, a spring mounted in a recess in said block, and means on the jack post arranged to act on the opposite ends of said spring to 95 determine a normal centralized position of said block while permitting it to be moved in opposite directions along the guideway against resistance of the spring.
- In testimony whereof I have signed my name to this specification. 100
